**CLOSED END SLEEVE-LIKE BOSS AND
METHOD OF MAKING**

Olayi M. Koškinen, Birmingham, Mich., assignor to Chrysler Corporation, Highland Park, Mich., a corporation of Delaware

Application May 19, 1954, Serial No. 430,863

2 Claims. (Cl. 207—6)

This invention relates to sleeve-like bosses that have knock-out integrally formed plugs that are removable so that the bosses may receive bolts or the like, and to the method of forming such bosses.

It is a primary object of this invention to provide a closed end, sleeve-like boss on which the end closure portion can be readily knocked out and the boss internally threaded to provide a satisfactory bolt receiving formation.

It is another object of this invention to provide a sleeve-like boss in which its method of forming work hardens the material forming the boss and thus improves its texture for machining, wearability, and the like.

It is still another object of this invention to provide a boss forming method that will provide relatively deep, symmetrical, sturdy, work-hardened bosses in relatively thin sheet stock.

It is still another object of this invention to provide a boss formation of suitable depth to provide a satisfactory bolt receiving bore wherein the boss formed is of a depth considerably greater than the thickness of the stock from which the boss is extruded.

It is still another object of this invention to provide a closed end sleeve-like boss formation that can be readily formed in relatively thin sheet stock without perforating the stock yet one in which the closed end portion of the boss formation may be readily removed by a knock-out operation that will not injure the adjacent sleeve portions of the boss.

It is also an object of this invention to provide an improved type of die for forming closed end, sleeve-type bosses.

It is still another object of this invention to provide an improved type of boss forming extrusion process.

Other objects and advantages of this invention will become readily apparent from a reading of the following description and a consideration of the related drawings wherein:

Fig. 1 is a fragmentary sectional elevational view of a punch type extrusion die used to form a boss embodying this invention, this view showing the beginning of the boss forming operation;

Fig. 2 is a view similar to Fig. 1 but showing the boss forming operation at a second stage;

Fig. 3 is a view similar to Figs. 1 and 2 but showing the boss forming operation at a third stage;

Fig. 4 is a view similar to Figs. 1—3 but showing the completion of the boss forming operation;

Fig. 5 is a sectional elevational view of a modified form of boss forming die having means associated with the punches for controlling the extrusion height or depth of the boss;

Fig. 6 is an enlarged fragmentary sectional elevational view of a boss formation of the type formed by the apparatus shown in Figs. 1—4;

Fig. 7 is a sectional elevational view of another modified form of extrusion die apparatus wherein only an upper punch and die block are utilized;

2

Fig. 8 is a fragmentary elevational view of an engine compartment fire wall having a plurality of compression extrusion formed closed end bosses formed therein;

Fig. 9 is a sectional elevational view taken along the line 9—9 of Fig. 8; and

Fig. 10 is a sectional elevational view of a portion of a fluid coupling casing formed with compression extrusion type, closed end, bosses in one of which a sealing plug has been mounted.

It has been common practice to punch a hole in a plate and to then thread the walls of the opening so as to provide a threaded recess to receive a bolt. This practice has been suitable for relatively thick plates but it is highly unsatisfactory for relatively thin plates because of the inadequate thread area that is provided.

In an attempt to provide additional stock thickness around the area where the plate is punched, attempts have been made to extrude or stretch the material removed from the punched out area into a collar or sleeve extending around the hole periphery. This has provided additional collar material around the punched out opening but this stretched material forming the hole collar has been stressed to such a degree during the punch-out process that it usually fractures at certain points around the collar periphery or, in the alternative, becomes so brittle that it cannot be properly machined during a thread forming operation.

The boss forming method herein disclosed redistributes the material acted on in the punch out area so that a sturdy, thick, symmetrical, collar is formed around the punch indented area. Furthermore, in the process of redistributing the stock material the material is work-hardened so that it is strengthened and improved as regards machinability and wearability. This method thus provides increased collar or boss depth for threading or bearing purposes and also gives an improved collar material that is stronger and more readily machined. In addition, it will be noted that this method initially provides a closed end, sleeve-type boss with a relatively thin knock-out plug rather than a completely pierced plate.

This is quite important for there are many applications where an imperforate plate is initially desired but one that may be readily pierced at one or more locations, subsequent to its fabrication, to provide an opening for receiving a bolt or the like. Several specific applications of such plates are subsequently described in referring to Figs. 8—10 of the drawings. By providing a plate that will completely seal off an area yet one that can be readily pierced by a simple knock-out operation, an important improvement has been achieved particularly when the knock-out operation leaves an opening surrounded by a sturdy, symmetrical collar of a depth considerably greater than the plate thickness.

In Figs. 1—4 of the drawings 10 represents the upper extruding punch that extends through an opening 11 in the stripper plate 12. P is the work piece or plate that is of a thickness t. The plate P is adapted to be supported on a die block 13 that has a stepped cylindrical bore or cavity 14 extending therethrough. Mounted in the cavity 14 of the die 13 is a lower extruding punch 16. Lower punch 16 may be reciprocably mounted in the die bore 14, as shown, or it can be rigidly associated with the die block 13. In the disclosed form the lower punch 16 is free to move vertically downward a limited amount because it is supported on a compression spring 18 that normally urges it upwardly off the die block seat 20. When a downwardly directed force is applied to the upper end of the lower punch 16 then the base 16a of the lower punch 16 compresses the spring 18 and the lower punch 16 seats on the die block seat portion 20 as shown in Figs. 2 and 4.

The several steps or stages in the formation of the im-

proved sleeve-type, closed end boss 30 will now be described. In Fig. 1 the several cooperating parts of the extrusion die apparatus are shown in the positions they assume when the boss forming operation is about to be initiated. At this time the spring 18 holds the lower punch 16 off the die block seat 20 and the upper end of the lower punch head 16b is pressed into engagement with the underside of the plate P.

As a downwardly directed force is applied to the upper punch 10, see Fig. 2, the head 10b of the upper punch 10 is forced into and depresses the portions of the plate P overlying the die cavity 14 and causes the lower punch 16 to move downwardly and seat on the die block seat portion 20. During this initial downward movement of the upper punch 10, the portion 25 of the plate P, located in the pressure area between the upper and lower punch heads 10b, 16b respectively, are first depressed a distance of approximately $\frac{1}{3}$ the thickness t of the stock P and then these portions of plate P are compressed and squeezed radially outwardly to begin the formation of the sleeve-like boss portions 30 by compressive extrusion.

As the downwardly directed force applied to the upper punch 10 is increased, see Fig. 3, upper punch 10 continues to compress and squeeze out the portions 25 of the plate P located in the pressure area between the punch heads 10b, 16b so that the plate portion 25 becomes progressively thinner while the compressed plate material squeezed from the plate portion 25 is entrapped in the die cavity 14 and redistributed in the peripheral area around the sides of the punch head 10b to form the sleeve-like boss formation 30. It will be noted from Figs. 3 and 4 that the increased punch applying forces, which cause compressive extrusion of the sleeve-like boss portions 30, also develop reaction forces which cause the plate P to rise up off the top of the die block 13. The space between the top of die block 13 and the plate P has been denoted by the reference numeral r in Figs. 3 and 4 and it is apparent from Figs. 3 and 4 that this reaction space r becomes progressively greater as the extrusion forces increase.

In applying this compressive extrusion process of boss formation to plates of several different thicknesses, it has been found that an excellent boss formation is achieved when (see Fig. 4) the depth of penetration x of the upper punch head 10b below the top of the die block 13, before compressive extrusion of the metal begins, is substantially one-third ($\frac{1}{3}$) the thickness t of the plate stock P. It is to be realized that this particular relationship is not critical but one that is merely recommended. Obviously this relationship will vary somewhat with the variations in plate thickness, boss diameter and height and material quality and hardness.

As previously pointed out one of the prime advantages of this invention over the prior art is the work hardening of the boss material during boss formation due to the compression extrusion of the boss material. This is a very definite improvement over the well known punch type of boss forming process wherein the plate material is stretched to boss form and tensile stresses are set up in the boss material rather than compressive stresses as with this process. It has been found that in forming bosses according to this process from plate material of $\frac{3}{16}$ inch thickness and 55 Rockwell D hardness that this compression extrusion process will provide a boss of about $\frac{3}{8}$ inch height or depth and that the hardness of the boss formation will have increased to about 100 Rockwell D (see Fig. 6).

In Fig. 5 is shown a modified form of boss forming extrusion die apparatus that is quite similar to the form of apparatus shown in Figs. 1-4 but differs therefrom in that the faces 50c and 46c of the upper and lower punches 50 and 46 respectively are each concavely dished. This dishing of the faces 46c, 50c of punch heads 46b, 50b provides an increased area between the punch heads into which the plate material may be squeezed during the com-

pression extrusion of the boss formations. In this manner the height or depth of the extruded boss 60 may be controlled while still providing for substantially the same upper punch penetration x beneath the top of the die block 13 before initiation of the compressive extrusion. The concavity of the punch end faces also provides a knock-out plug 55 that has a thin outer periphery and a thick center and this makes the plug 55 easier to knock out.

Fig. 6 shows an enlarged view of a portion of a plate P having a closed end boss 30 formed therein according to the teachings of Figs. 1-4. Material of the boss 30 that has been work hardened during its process of formation has been labeled to indicate a hardness of 100 Rockwell D whereas the plate P from which the boss 30 was formed initially had a hardness of only 55 Rockwell D. It will also be noticed that the radius of curvature c at the base of the boss 30 is relatively large and this prevents an undesirable stress concentration at this portion of the boss and adds to its strength.

Fig. 7 is a view of another type of extrusion die apparatus similar to that shown in Figs. 1-4. In this case, however, the lower punch 16 is completely omitted. This type of die is suitable for certain types of boss formations but does not give the accuracy obtainable with the die apparatus shown in Figs. 1-4. The Figs. 1-4 apparatus seems more proficient in maintaining the centered position of the upper punch 10 with respect to the die block opening 14 so as to prevent cocking or tilting of the upper punch 10 with respect to the plate P and the die cavity 14. Die block 13a in the Fig. 7 form of the invention merely has a cylindrical cavity 14a formed in its top surface that is axially aligned with the upper punch 10. The upper punch head 10b penetrates the die block cavity 14a substantially the full depth of the cavity but leaves a thin space between its end face 10c and the bottom of the cavity 14a. This space provides for the thin knock-out plug 25a that seals off the end of the sleeve-like boss 70. As with the forms of die apparatus shown in Figs. 1-5, this form of device also work-hardens the boss material due to the compression of the boss material during formation thereof.

Figs. 8 and 9 show a portion of a vehicle engine compartment fire wall having a plurality of closed end sleeve-type bosses 30 formed therein. In this case two of the bosses have had their knock-out plugs 25 removed and an accessory A has been bolted in these two open ended bosses by means of self tapping bolts 36. If at some later time additional accessories should be required, then the knock-out plugs 25 in some of the other bosses 30 could be removed. In the mean time the integral plugs 25 provide an air tight seal between opposite sides of the fire wall D. It will also be noted that the bosses 30 formed by this compression extrusion process do not have sharp edges so they are suitable for ports for electrical wiring without the use of special wire supporting bushings to prevent cutting or wear of the wire insulating casings.

Fig. 10 shows the application of this compression method of boss extrusion to the casing of a fluid coupling. In this case one of the knock-out plugs 25 has been removed and a tapered screw plug 38 has been threaded into the open ended boss 30. While only a few examples of the utility of this type of boss formation have been shown, it is thought to be obvious that vehicle door hinge plates and pulley hubs and innumerable other parts of a motor vehicle could have this invention applied thereto. The applications of this invention to industries other than the motor vehicle industry are too numerous to even mention. Due to this invention permitting the use of thinner sheet stock while giving increased thickness of boss formations, considerable weight and cost savings can be achieved and for that reason this invention will be of considerable importance in the aircraft industry.

I claim:

1. The method of forming a relatively thick walled, sleeve-type, closed end, boss in a relatively thin sheet of

material comprising depressing a circular area therein to form a concavity in said sheet until the underside of the depressed area lies below the general plane of the underside of the sheet material a distance approximately one-third the thickness of said sheet, thereafter continuously and progressively compressing the center portion of the depressed area of said concavity by applying pressure to the opposed inner and outer bottom sides of said depressed center portion without bodily displacing said center portion to subject the intervening material to a squeeze action thereby extruding the material thereof in directions transversely of the compressing force and entrapping said extruding material coupled with redistribution thereof in all directions parallel to the direction of the compressing force to form a thick walled, sleeve-type, boss, closed by the remaining material of said squeezed central portion.

2. The method of forming a relatively thick walled, sleeve-type, closed end, boss in a relatively thin sheet of metal comprising depressing an annular area therein to form a concavity in said sheet until the underside of the depressed area lies below the general plane of the underside of the metal sheet a distance approximately one-third the thickness of said sheet, thereafter continuously and progressively compressing portions of the bottom of said depressed area of said concavity by applying pressure to the opposed concave and convex sides of said depressed bottom portion without bodily displacing said depressed bottom portion to subject the intervening metal to a

5 squeeze action thereby extruding the metal thereof in directions transversely of the compressing force and entrapping said extruding metal at the outer periphery of said depressed bottom portion coupled with redistribution 10 of the entrapped extruding metal in all directions parallel to the direction of the compressing force to form a thick walled, sleeve-type, boss, closed by the remaining metal of said squeezed portion.
